UNITED STATES PATENT OFFICE.

JOHN A. BOEHRINGER, OF SPRINGFIELD, NEW YORK, ASSIGNOR TO HERMAN A. SAFION, OF NEW YORK, N. Y.

DESIGN FOR A CANDLE CUP FOR LIGHTING FIXTURES.

Application filed January 10, 1925. Serial No. 12,003. Term of patent 3½ years.

To all whom it may concern:

Be it known that I, JOHN A. BOEHRINGER, a citizen of the United States, residing at Springfield, in the county of Queens and State of New York, have invented a new, original, and ornamental Design for a Candle Cup for Lighting Fixtures, of which the following is a specification, reference being had to the accompanying drawing, forming part thereof.

Figure 1 is a plan view of a candle cup for lighting fixtures, showing my new design; and Fig. 2 is a side elevation thereof.

I claim:

The ornamental design for a candle cup for lighting fixtures, as shown.

JOHN A. BOEHRINGER.
